UNITED STATES PATENT OFFICE.

WALTER STOFFEL, OF GREENLEAF, KANSAS.

CYLINDER-TOOTH.

1,167,667.

Specification of Letters Patent. Patented Jan. 11, 1916.

Application filed April 7, 1915. Serial No. 19,731.

To all whom it may concern:

Be it known that I, WALTER STOFFEL, a citizen of the United States, residing at Greenleaf, in the county of Washington and State of Kansas, have invented certain new and useful Improvements in Cylinder-Teeth, of which the following is a specification.

My invention relates to an improved tooth means, designed to be used in conjunction with a threshing machine cylinder structure, which is reversible to present complementary facing members, one of which may be moved to supplant the other after the latter has become worn.

The object of my invention is to provide a tooth means that is reversible, materially increasing the longevity thereof, and wherein the facing members can be removed and reversed without causing the tooth to be detached from the cylinder bars.

The above and other objects are accomplished by such means as are shown in their preferred form in the accompanying drawings, described in the following specification and more specifically pointed out in the appended claims.

In the drawings like numerals designate like parts throughout the several views and in which:

Figure 1 is a fragmentary view showing the usual form of threshing machine cylinder in section and illustrating my improved tooth means in conjunction therewith. Fig. 2 is a side elevation of my invention showing the facing member removed. Fig. 3 is a vertical sectional view of the facing member. Fig. 4 is a transverse sectional view of the facing member. Fig. 5 is an edge view of the supporting means for the facing member. Fig. 6 is a detail view showing a fastening member which is used.

In the drawings I have shown my invention in correlation with a threshing machine cylinder structure of the usual construction, yet it is to be understood that my device is not limited to such employment and that the same may be arranged in connection with cylinder structures of other types if it is so desired.

Referring now to the construction illustrated, the cylinder 10 consists of a multiplicity of transversely arranged tooth supporting bars, of a modern type and usually co-acts with the remaining threshing mechanism (not shown).

During the operation of the cylinder, it has been found that the wearing face of the teeth, exposed to the resistance co-acting mechanism, will become worn to an extent whereby it will derivate from the efficiency of the machine. When this occurs, the worn tooth is replaced, and in some instances an independent facing member is substituted. It is evident therefore that the longevity of the tooth is materially increased.

As set forth above, my invention includes a facing member presenting complementary wearing structures which are reversible in order that one of the wearing structures may be substituted for the other after the latter one has become worn.

In consistence with the foregoing, I employ a tooth element for supporting the improved facing structure, which includes a shank 11. With view of accommodating a fastening member 12, a portion of the shank is provided with screw threads 13, yet I desire to point out that other fastening means may be substituted if it is so desired. The opposite terminal of the shank is enlarged to form opposite squared shoulders 13 and 14 respectively, which are provided with a transverse opening 15 and serve the purpose that will presently appear.

Preferably formed integral and arranged in a corresponding plane with the shoulder portions 13 and 14, is a tapering supporting structure 16 designed for the purpose of receiving the facing member as will be hereinafter described. The structure 16 is beveled adjacent its longitudinal edges and free end as at 17 in Fig. 5, whereby a more efficient connection with the facing member may be obtained. The longitudinal edges of the structure 16 being spaced from the respective terminals of the shoulders 13 and 14, provide opposite supporting projections 18.

My improved facing member consists of a substantially U-shaped structure including a body portion 19 and spaced apart arms 20. It is here pointed out that the inner faces of the arms 20 are beveled at an angle similar to the degree of tapering of the supporting structure 16.

Oppositely arranged flanges 21 depend from the opposite faces of the arms 20 and 10 from the inner face of the body 19. The inner opposite faces of the flanges are cut at an angle as shown at 22 for forming a continuous beveled way for receiving the correspondingly formed portion of the supporting structure 16.

It is pointed out that the terminals 23 of the flanges 21 terminate short of the respective ends of the arms 20 and when the facing member is in an operative position, about the faces of the supporting projections 18 to serve as an auxiliary means for attaining the complete rigidity of the structure.

Openings 24 are arranged adjacent the 25 respective terminals of the arms 20 and are adapted to register with the opening 15 in the shoulders 13 and 14, for accommodating a fastening element 25. The co-action between the fastening element 25 and 30 the wedging action resultant from the abutment of the lower ends of the flanges and the projections 18, is thought to be readily apparent. It is further obvious that this 35 method of fastening forms an important feature of the device, as the positive rigidity of the fastening member is assured.

In operation the shank 11 is first disposed through an adjacent angle bar 10, after which the fastening element 12 is operated 40 so as to draw the enlargement 26 of the shank into binding engagement therewith. This specific fastening arrangement serves to hold the shank rigid upon the cylinder during the operation thereof. The facing member is now disposed over the supporting structure 16, the openings 24 and 15 coinciding to allow the insertion of the fastening member 25. As set forth above, the co-action between the beveled faces of the 45 supporting structure 16 and the correspondingly formed opposite faces of the flanges 21 is thought to be readily obvious. This means prevents the lateral displacement of the fastening member while in operation, 50 and also serves to attain a uniform rigidity between the fastening member and its supporting structure.

The material used in the construction of my improved tooth means may be varied to 60 prove efficient under the existing circumstances.

In reducing my invention to practice, I find that the form referred to herein as

the most practical and preferred embodiment is the most efficient; but realizing that 65 certain conditions will necessarily vary in concurrence with the adoption of my device, I desire to emphasize the fact that various minor changes in the details of construction and proportion of parts may be resorted to 70 when required, without sacrificing any of the advantages of my invention as defined in the appended claims.

Having thus fully described my invention, what I claim as new and desire to secure by 75 Letters Patent is:

1. In a device of the character described, a shank structure, a support on said shank structure, opposite shoulders arranged intermediate said shank structure and said support and projecting beyond the longitudinal edges thereof, a reversible facing member carried on said support and engaging the outer faces of said shoulders and means detachably connecting said shoulders 85 and said member, substantially as described.

2. In a device of the character described, a shank structure, a support arranged at one end of said shank structure, shoulders formed intermediate said support and said 90 shank structure, a substantially U-shaped facing member carried on said support and engaging the outer face of said shoulder and means connecting said member and said shoulders, substantially as described. 95

3. In a device of the character described, a shank structure, a supporting structure formed integral therewith, opposite shoulders formed from said shank structure, a facing member, opposite flanges arranged 100 on said facing member and adapted to engage the respective sides of said supporting structure, said supporting structure being beveled adjacent its respective longitudinal edges and adjacent the free end thereof, the 105 inner opposite faces of said flanges being beveled for engagement therewith, and means for securing said facing member to said shoulders, substantially as described.

4. In a device of the character described, 110 a shank structure and supporting structure formed integral therewith, opposite shoulders arranged intermediate said supporting structure and said shank structure, a facing member, opposite flanges carried by said 115 facing member and embracing said supporting structure, and fastening means extending through said shoulders and having connection with said facing member, substantially as described.

5. In a device of the character described, a shank structure, a supporting structure formed integral therewith, shoulders formed intermediate said support and said shank and projecting beyond the longitudinal 125 edges thereof, a substantially U-shaped

member, inwardly projecting flanges formed on said facing member to embrace said supporting structure, said facing member engaging the outer faces of said shoulders, 5 and a fastening member extending through aligned openings in said shoulders and said facing member, for the purpose specified.

In testimony whereof I affix my signature in presence of two witnesses.

WALTER STOFFEL.
